UNITED STATES PATENT OFFICE

101,257

DESIGN FOR A MESH FABRIC FOR A CUR- TAIN OR SIMILAR ARTICLE

Max Sadinoff, New York, N. Y.

Application June 17, 1936, Serial No. 63,339

Term of patent 3½ years

To all whom it may concern:

Be it known that I, Max Sadinoff, a citizen of the United States, residing in the Borough of Bronx, county of Bronx, city of New York, and State of New York, have invented a new, original, and ornamental Design for a Mesh Fabric for a Curtain or Similar Article, of which the following is a specification, reference being had to the accompanying drawing, forming a part thereof.

The design is an open mesh fabric as shown by the drawing in which Fig. 1 represents a plan view of the fabric, the cut-away portion indicates repetition of the design most nearly ad-

jacent thereto, and Fig. 2 is an enlarged view of the section within the rectangle *r*.

The design is further characterized by a pair of bars 6 of color in contrast with the color of the rest of the material, said bars running near and parallel to each vertical edge.

I claim:

The ornamental design for a mesh fabric for a curtain or similar article as shown and described.

In testimony whereof I have signed this specification.

MAX SADINOFF.
